COIL SPRING CUTTER

Ralph E. Williams and Leon J. Nowak, Jr., Chicago, Ill., assignors to Gardner Wire Co., Chicago, Ill., a corporation of Illinois

Application November 28, 1947, Serial No. 788,576

4 Claims. (Cl. 164—36)

1

Our invention relates to improvements in cutters for coil springs and the like and has for one object to provide a new and improved form of cutter whereby the length of spring to be cut may be measured, and cut without distortion, and whereby the spring after cutting will be anchored to prevent the parts flying through the air as the result of the cutting action.

Another purpose is to provide a cutter which is highly efficient in cutting other articles and other materials.

Other objects will appear from time to time throughout the specification and claims.

Coil springs are made of stiff, hard wire, and it is usually of the utmost importance to be able to cut the spring accurately in length. Because of the hardness of the wire, the spring tends, when cut, to fly through the air, causing breakage and damage, and we propose, therefore, to associate with the cutter an accurate measuring device, and also to associate with the cutter means for anchoring both that part of the spring which is cut off and the remaining part of the spring so that even when cut, the spring and spring parts will remain in the same general position assumed by them before the cutting action.

Preferably the knife and the abutment are both of carboloy or some similar exceedingly hard, inflexible material. So any substantial pressure on the side of the knife must be avoided, as otherwise the knife will break or chip. The same is true with respect to the clearance between the knife and the abutment in the final position. The two must not quite touch, because if they do, they will chip. This explains the necessity of accurate adjustment of the clearance between blade and anvil. They must come almost to contact, else the wire will not be cut. They cannot touch, or else the tool will be damaged.

The slots through which the coil spring is passed to put it in position for cutting are elongated in the direction of movement of the member that applies the cutting force. Thus the spring is at all times free to have a sufficient amount of longitudinal movement to permit the blade to penetrate between the coils of the spring without the application of any lateral pressure on the blade. After the blade has penetrated between the spring coil, further movement of the tool applying the cutting force continues until the coiled wire itself is held between the cutting knife and the abutment or blade, at which time, because of the toggle effect, maximum pressure is applied to cut the wire, and this pressure is

2

always in line with the direction of movement of the cutting elements so that any breaking or chipping or bending of the knife is avoided.

Our invention is illustrated more or less diagrammatically in the accompanying drawings, wherein:

Figure 1 is a perspective view of the cutting device;

Figure 2 is a section along the line 2—2 of Figure 1;

Figure 3 is a section along the line 3—3 of Figure 2;

Figure 4 is a section along the line 4—4 of Figure 3;

Figure 5 is a detail section on an enlarged scale showing the spring about to be cut;

Figure 6 is a section on a smaller scale along the line 6—6 of Figure 5;

Figure 7 is a detail on the same scale as Figure 5 showing the cut end of the spring;

Figure 8 is a plan view in part section showing a modified form of the mounting and adjustment of the blade in the guides, and also a modified form of scale;

Figure 9 is a side elevation of the parts shown in Figure 8;

Figure 10 is a section along the line 10—10 of Figure 9;

Figure 11 is a partial perspective view of a further modification; and

Figure 12 is a section on the line 12—12 of Figure 11.

Like parts are indicated by like characters throughout the specification and drawings.

1 is a cutting tool base. Mounted thereon are two opposed angle members 2, 3, the bases of the angle being parallel to the base 1, each angle having an upwardly extending flange 4, 5. 6 is a knife block held between the angle flanges 4, 5, by a pin 7. The knife block has forwardly projecting a thin, vertical cutting tool or knife 8 terminating in a vertical, sharp cutting edge 9. This tool 8 is removably held in the knife block 6. Outside of the flanges 4, 5, also held by the pin 7, are holding blades 10, 11. These holding blades do not extend quite as far forward as does the knife 8.

12, 13 are toggle members, the member 12 being pivoted at 14 between the flanges 4, 5, the members 12 and 13 being pivoted together by a pin 15, the member 12 having a groove, the member 13 a tongue engaged by the pin 15. 16 is an operating handle on the member 12. 17 is a block held by screws 18 to the outer end of the member 13, and 19 is an anvil face held by a screw 20 to

55

the member 17 overlying the end of the toggle member 13. This anvil face 19 is removable and narrower than the width of the member 13.

The flanges 4, 5 are immediately in front of the knife block 6 provided with elongated apertures 22 to admit a coiled spring to be cut. In alignment with these apertures 22 is a scale plate 23 mounted on one of the flanges and extending laterally therefrom at right angles to the flanges 4, 5. This scale plate is provided with scale markings 24, 25 so that a spring may be laid upon them and the distance between the end of the spring and the point at which the spring is to be cut may be directly read from the scale markings.

The knife block shown in Figures 8, 9 and 10 is adjustably mounted between the flanges 4 and 5. 30 is a threaded abutment plate anchored between the flanges 4 and 5 on the base so as to be held against any displacement. 31 is a screw threaded in the block 30. It engages a knife block 32. 33 is a bolt extending through the flanges 4 and 5, these flanges having elliptical apertures 34 to permit lateral movement of the bolt. 35 is a nut threaded on the bolt, adapted to exert tension to grip the block 32 between the flanges 4 and 5. 36 is a knife held in a slot 37 in the knife block by means of a set screw 38. The end of the screw 31 fits into a socket 39 at the rear end of the knife block, so that when the nut 35 is released the screw 31 may be adjusted to microscopically adjust the position of the knife and knife block with respect to the forward excursion of the anvil 19.

In Figures 8, 9 and 10 also is shown a modified form of measuring scale. It includes an angle member 40 pivoted at 41 on the base 2, having an angular scale member 42 mounted thereon by screws 43 so that the scale may be swung laterally into alignment with the cutter for storage, and may be rotated into the position shown in Figures 8, 9 and 10 for use. 44 is an aperture in the base 1 through which chips may drop out. Figure 8 shows in dotted lines the position assumed by the scale 42 and support 40 when not in use.

In the form of Figures 11 and 12 we obtain the further advantage that the ruler 100 moves in unison with the toggle 101. Thus the work and the ruler may move in unison, and the user finds it easy to maintain a proper and accurate position of cut. Since the ruler goes forward with the work, the spring is being accurately measured up to the instant at which it is cut. We obtain the above result by providing an outward extension 103 of the toggle, the ruler being pivoted as at 104, so that it can readily be swung back into position over the base for convenience in packing and storing.

The use and operation of our invention are as follows:

The spring from which a length is to be cut is inserted through the apertures 22 and moved forward between the knife block 6 and the anvil 19 until the desired length to be cut is read off on the scales 24 and 25. The block 17 and anvil 19 which will normally be in the position generally shown in Figure 2 rather than in the position shown in Figure 1, which latter is provided primarily for the purpose of illustration only, will then be moved toward the knife block 6 by pressure applied to the handle 16. This results first in causing the cutting blade 8 to penetrate between two of the spring coils as indicated in Figure 3. At the same time as the spring is moved by the movement of the toggle members 12, 13 to the

left in Figure 3, the blades 10 and 11 will also penetrate between the coils and so the spring will be anchored on both sides of the flanges 4 and 5. Further downward movement of the lever 16 will cause the toggle to exert an increased pressure sufficient to force the member 19 toward the blade, thus forcing the spring against the cutting member 8 to cut the wire and so cut the spring. When this takes place, the spring will still be held anchored by the blades 10 and 11 so there is no explosive leap of the spring from the point of cut-off. The raising of the lever 16 permits disengagement of the cut-off portion of the spring from the blade 11 and the residual portion of the spring from the blade 10, when both parts of the spring may be withdrawn from the cutter.

Because the scale markings 24 and 25 extend across the scale bed 23, the operator is able by observation to determine that he has properly positioned the spring for cutting to the suitable length right down to the time when the spring is about to be cut, thus avoiding the danger of cutting a spring of improper length.

An important application of our device is to cut materials, other than metal, which may be difficult to cut or resistant to ordinary cutters. For example, our cutter cuts tubing of rubber or rubber substitutes or softer plastics, with or without reinforcing of wire, and textiles or other material. It is also an efficient cutter of plain wire of various gauges and hardness.

It will be realized that whereas we have described and shown a practical and operative device, nevertheless many changes may be made in size, shape, number and dispositions of parts without departing from the spirit of our invention. We therefore wish our showing to be taken as in a broad sense illustrative or diagrammatic, rather than as limiting us to the structures specifically described and shown herein. For example, we wish it understood that we may employ an anvil on one relatively movable member, and a blade on the other. It is immaterial whether the anvil is on the moving or on the fixed part of the device. 45 Or both may be movably mounted for movement toward and away from each other. Under some circumstances, instead of having an extended or smooth-surfaced anvil, we may employ a pair of opposed cutting blades. It is advantageous, however, to employ a plane-surfaced or a smooth-surfaced anvil. Whereas the anvil has been shown as plane surfaced, it will be understood that a smooth surface may be employed which is not strictly plane. A smooth-surfaced anvil has as 50 one advantage the fact that it permits the work, such as the coil spring, to take a natural position in relation to the blade, as the blade penetrates between adjacent coils of a coil spring. It will therefore be understood that we do not wish our 55 claims to be limited except so far as they are specifically limited in their language.

Whereas in the claims we describe "forcing the blade and the abutment surface together to cut the wire," it will be understood that we do not wish to have the word "together" interpreted as necessitating actual contact of the opposed blade and abutment.

It will also be understood that it is optional whether we employ a removable anvil or abutment, or one which is not removable or replaceable. In general, however, we find it advantageous to employ a removable and renewable anvil, as shown at 19 in Figure 2.

When our tool is used for cutting rubber or

resilient tubing, an advantage is that the tubing is initially compressed, along the length of the entire cut, and is then severed. This produces a straight cut, in contrast to the action obtained by a pair of shears, where only a small portion is compressed at a time.

We claim:

1. A coil-spring-cutting means including a plurality of blades adapted to penetrate between the coils of a spring, one of the blades extending further toward the coil than the other, an anvil having a face in opposition to the blade which extends furthest toward the coil spring, means for forcing such blade and such anvil together to cut the wire forming the coil.

2. A coil-spring-cutting means including a plurality of blades adapted to penetrate between the coils of a spring, one of the blades extending further toward the coil than the other, an anvil face in opposition to the blade which extends furthest toward the coil spring, means for forcing such blade and such anvil together to cut the wire forming the coil, apertured members through which the coil to be cut may be passed, said apertured members being in immediate juxtaposition to the shorter blade.

3. Severing means for coil springs and the like, including a cutting blade adapted to penetrate between the coils of the spring, said cutting blade having a terminal and generally parallel side faces which, for a distance from the cutting edge at least equaling the diameter of the spring to be cut, are separated by a thickness of metal insufficient damagingly to distort the spring, an abutment member in opposition to the blade, means for forcing the blade and the abutment member together to cause the blade to penetrate between the coils of the spring, engage one of the coils beyond such penetration, and cut the coil against the abutment member to sever

the coil, a keeper blade parallel with the blade but terminating short thereof, said keeper blade being adapted to penetrate between adjacent coils of the spring at a point removed from the point of severing so that after the spring is severed, the keeper blade holds the spring in place.

4. Severing means for coil springs and the like, including a cutting blade adapted to penetrate between the coils of the spring, an abutment member in opposition to the blade, means for forcing the blade and the abutment member together to cause the blade to penetrate between the coils of the spring, engage one of the coils beyond such penetration, and cut the coil against the abutment member to sever the coil, longitudinal guide means enclosing the blade and the abutment member, the guide means being longitudinally slotted, whereby the coil spring may be positioned between the blade and abutment member as it passes through the slots, keeper blades parallel with the cutting blade, one associated with each guide on the side thereof opposed to the cutting blade, the keeper blades being adapted to penetrate between coils of the spring spaced from the coil engaged by the cutting blade when the cutting blade and the abutment member are brought together to engage and sever the spring.
